C. KAISER

ELECTRIC INDUCTION WATER HEATER

Filed March 25, 1922.

INVENTOR
Charles Kaiser.

BY
Fred G. Dietrich, Esq.
ATTORNEYS

UNITED STATES PATENT OFFICE.

CHARLES KAISER, OF ATLANTIC CITY, NEW JERSEY, NOW BY JUDICIAL CHANGE OF NAME CHARLES CAISE

ELECTRIC-INDUCTION WATER HEATER.

Application filed March 25, 1922. Serial No. 546,704.

To all whom it may concern:

Be it known that I, CHARLES KAISER, a citizen of the United States, residing at Atlantic City, in the county of Atlantic, and State of New Jersey, have invented certain new and useful Improvements in Electric-Induction Water Heaters, of which the following is a specification.

My invention has for its object to provide a heater of the electric-induction type which is especially useful in house heating systems and by means of which the water in a hot water circulating system may be raised to the desired temperature quickly and efficiently. Another object of the invention is to provide such a heater wherein the secondary of the transformer consists of a winding of tubing, i. e. coiled pipe (preferably copper), which is connected in the water circulating circuit and around which tube-winding the primary wire-winding of the energizing circuit is placed. Again it is an object to provide an induction heater of the construction stated wherein the primary coils are so wound as to be connected to the terminal leads of a three wire circuit in a manner so that one-half of the heater may be operated alternately, or both halves may be operated simultaneously, as conditions may justify.

A further object of the invention is to provide an induction heater wherein a secondary coil, consisting of a few turns of piping, is wound around a laminated core and heat insulated therefrom and wherein a primary coil of many turns of wire is wound around and heat insulated from the secondary pipe-coil, means being provided for ventilating the core and the primary coil to prevent overheating the same.

In its more specific nature, the invention also resides in those novel features of construction, combination and arrangement of parts, all of which will be first fully described, then be specifically pointed out in the appended claims, reference being had to the accompanying drawings, in which:

Figure 1 is a diagrammatic view illustrating one way of using my invention.

Figure 2 is a side elevation and part vertical longitudinal section of the heater per se, taken substantially on the line 2—2 of Figure 3.

Figure 3 is a plan view and part horizon-

tal section taken substantially on the line 3—3 of Figure 2.

In the drawings in which like numerals and letters of reference designate like parts in all of the figures, A represents the heater constituting my invention. B indicates one of the radiators of a hot water heating system, C a cold water tank which is preferably located at an elevation just above the heater A and receives its supply from the return lead of the radiator B and which has its outlet connected by a duct to the inlet end of the secondary pipe-coils of the heater A, the outlet of which pipe-coils is connected to the riser which leads the water to the radiator B as indicated diagrammatically in Figure 1. From the diagram Figure 1 it will also be noted that the primary coils of the heater have one each of their terminals connected to the neutral wire d of the three wire circuit D through a knife switch at S, while the other terminals of the respective primary coils of the heater are connected with the leads d' and d'' of the three wire system through knife switches at S. The foregoing is a mere diagrammatic illustration of one way in which my invention may be used but, of course, it is to be understood that any number of radiators may be connected up with one heater according to the capacity of the heater.

The heater which, per se, constitutes the essential part of my invention is constructed on the principle of a step down transformer. By reference especially to Figures 2 and 3, the construction of my heater will, it is thought be clearly understood. In the drawing the core of the transformer-heater is composed of laminæ and may be of any of the usual forms used in transformer constructions and the laminæ may be packed together in any of the usual ways. Spaced from the laminated core 1, at 7, are placed shells 2 of asbestos or other suitable heat insulating material and around these shells 2 are wound, in few turns, coils of pipe 3 through which the water to be heated circulates. Around these coils of pipe 3 is another shell 4 of asbestos or other suitable heat insulating material and around these shells 4 (preferably spaced therefrom at 7) are located the primary-wire coils 5 that connect with the source of current supply as above indicated. While it is preferable to

leave the spaces 7 between the shells 4 and coils 5, they may be dispensed with and the coils wound directly around the asbestos, if desired, and by leaving the spaces 7 between 5 the shells 4 and coils 5 and by leaving the spaces 7 between the core 1 and the shells 2, I am enabled to provide ventilation so that the heat generated in the pipe coil 3 will not be conducted to the core 1 or the primary 10 coil 5 and thus prevent overheating of the primary coil and of the core. It is especially desirable to prevent overheating at the core since when the core becomes overheated, its efficiency is lowered. In order to provide 15 circulation of air through the passages or spaces 7, the end insulation disks 6 are apertured at 8.

The ends of the coils 3 where they project beyond the heater proper are bridged by 20 short circuiting fuse wires 9 so as to cause the current flow to heat up the coils 3 and in consequence heat the water passing through the same.

While I have not illustrated it, the heater 25 may be iron-clad or enclosed in an iron shell to increase the magnetic circuit of the core as is common practice in transformer building and I desire it understood that I do not wish to be limited in the details of construction 30 as many modifications of the invention will be apparent to those skilled in the art, the essential feature of my invention being the provision of the secondary coil or piping or tubing in which current may be caused 35 to flow by induction and which serves as the secondary winding of the transformer-heater.

I am aware that heretofore transformer-heaters have been provided. These are 40 usually of the type in which the core acts as the water duct and is heated up to a temperature sufficient to warm the water but where the core is heated the efficiency of the apparatus is lowered and my invention has 45 been provided to avoid this objection.

I am also aware that electric water heaters have been provided in which the secondary coil consists of a single loop of solid 50 conductor material in the form of a U-shaped member between the ends of which is coiled a short section of pipe, the axis of which coil is at right angles to the leg of the core around which the conductor loop passes. I am also aware that electric water heaters 55 have been provided in which the secondary coil consisting of a pipe is wound around the core of a transformer field piece and the primary coil of wire is wound around the core separately from the secondary coil, but I am not aware of any construction heretofore suggested embodying the essential 60 feature of winding the wire coil around the pipe coil and the core as a secondary winding.

From the foregoing description, taken in

connection with the accompanying drawing, it is thought the construction, operation and advantages of my invention will be clear to those skilled in the art.

What I claim is:

1. In an induction heater, a core, a secondary coil wound around said core, a primary coil of wire wound around said secondary coil, said wire coil having provision for connecting it to an electric energizing 75 circuit, said secondary coil comprising a pipe adapted for connection in a water circulating circuit, and heat insulating means separating said pipe-coil from said core.

2. In an induction heater, a core, a secondary coil wound around said core, a primary coil of wire wound around said secondary coil, said wire coil having provision for connecting it to an electric energizing circuit, said secondary coil comprising a 85 pipe adapted for connection in a water circulating circuit, heat insulating means separating said pipe-coil from said core and heat insulating means separating said pipe-coil from said wire-coil.

3. In an induction heater, a core, a secondary coil wound around said core, a primary coil of wire wound around said secondary coil, said wire coil having provision for connecting it to an electric energizing circuit, 95 said secondary coil comprising a pipe adapted for connection in a water circulating circuit, heat insulating means separating said pipe-coil from said core and a fuse wire short circuiting the ends of said pipe-coil.

4. In an induction heater, a core, a secondary coil wound around said core, a primary coil of wire wound around said secondary coil, said wire coil having provision for connecting it to an electric energizing circuit, 105 said secondary coil comprising a pipe adapted for connection in a water circulating circuit, heat insulating means separating said pipe-coil from said core, heat insulating means separating said pipe-coil from said wire-coil, and a fuse wire short circuiting 110 the ends of said pipe-coil.

5. In an induction heater, a core, a heat insulating shell on said core and spaced from the same to form an air circulating chamber, 115 a secondary coil of pipe wound around said insulating shell, a second insulating shell located around said pipe, a third insulating shell encircling said second insulating shell and spaced from the same, insulating disks 120 on said core at the ends of said shells with air circulating passages communicating with the spaces between the second and third insulating shells and between the first insulating shell and the core, and a primary coil, 125 adapted to be connected with an electric energizing circuit, wound around said third insulating shell, said secondary coil adapted for connection in a water circulating circuit.

6. In an induction heater, a core, a coil unit mounted on said core, said unit comprising end disks, a central insulating shell of greater diameter than the thickness of said core and adapted to fit on said core to leave a passage between the shell and the core, a secondary pipe-coil wound around said shell and having its ends projected through apertures in said end disks and adapted to be connected to a water circulating circuit, a primary energizing coil wound between said end disks around said pipe-coil, means for spacing said primary energizing coil from the said pipe-coil and insulating the same, said means including an air chamber, said end disks having air ports adapted to communicate with said air chamber and having air ports adapted to communicate with the interior of said shell around said core. 20
7. In an induction heater, a core, a secondary coil wound around and spaced from said core, said secondary coil comprising a pipe adapted for connection in a water circulating circuit, a primary coil of wire wound around and spaced from said secondary coil, the spaces between said primary coil and said secondary coil and the spaces between said secondary coil and said core constituting cooling spaces for the purposes 25 30 described.

CHARLES KAISER.
